UNITED STATES PATENT OFFICE

2,561,577

PNEUMATIC IMPACT PULLER AND THE LIKE

Raymond G. Knudsen, Kenosha, Wis., assignor to Snap-On Tools Corporation, Kenosha, Wis., a corporation of Delaware

Application August 1, 1947, Serial No. 765,312

4 Claims. (Cl. 121—13)

1

This invention relates to article pulling devices and more particularly to pneumatic pullers to facilitate the removal or withdrawal of articles from their supporting elements, although certain features thereof may be employed with equal advantage for other purposes. It contemplates more especially the provisions of an improved combination impact puller that is power actuated to dislodge an article from its supporting element without entailing any appreciable time or effort.

Numerous types of pullers have heretofore been proposed and manual impact pullers are also old in the art as illustrated by United States Letters Patent No. 1,893,414 issued January 3, 1933. This type of impact puller has operated very satisfactorily for dislodging gears, pulleys and similar articles from their studs or shafts. Such articles require only several impacts to effect dislodgement, but modern devices, such as tractor and truck engines, embody removal sleeves to line the cylinder walls which require replacement from time to time. These sleeves are pressed into the cylinders with an appreciable load so that their removal is rather difficult unless an efficient power actuated pulling device is employed. Numerous types of power pulling tools have been devised for this and other purposes but these are, for the most part, rather slow in operation and comprise too much bulk so that they are not readily portable to the extent of affording efficient use in all types of situations where tools of this character are of value.

One object of the present invention is to simplify the construction and improve the operation of devices of the character mentioned.

Another object is to provide an improved power actuator pulling device which is compact, speedy, and an effective article puller.

Still another object is to provide an improved pneumatic power article puller that is light in weight, speedy in operation, and effectively dislodges articles from their supporting medium.

A further object is to provide an article puller of the vibratory impact type for dislodging articles from their supporting element.

A still further object is to provide a pneumatic impacting article puller that effectively separates elements that are tightly joined together and require appreciable relative displacement for complete dislodgement.

Still a further object is to provide an improved portable power pulling device of the impact type which is capable of imparting relative displacement to tightly connected articles to effect their complete separation.

2

Other objects and advantages will appear from the following description of an illustrative embodiment of the present invention.

In the drawings:

5 Figure 1 is a sectional view in elevation of an impacting sleeve puller device embodying teachings of the present invention.

10 Figure 2 is a view similar to Figure 1 of a modified embodiment of the present invention showing its adaptation as a gear puller.

15 Figure 3 is a sectional plan view taken substantially along line III—III of Figure 1.

20 Figure 4 is a sectional plan view similar to Figure 3 with the sleeve engaging member disposed normally of the position illustrated in Figure 3 whereby it can be displaced downwardly through a cylinder sleeve for engagement with the lower peripheral edge thereof preparatory to effecting its removal.

25 Figure 5 is a sectional plan view taken substantially along line V—V of Figure 2.

30 Figure 6 is a sectional plan view taken substantially along line VI—VI of Figure 1.

35 Figure 7 is a sectional plan view taken substantially along line VII—VII of Figure 1.

The structure selected for illustration is not intended to serve as a limitation upon the scope or teachings of the invention, but is merely illustrative if all or part of the teachings depending upon the dictates of commercial practice. The present embodiment comprises a shank or elongated shaft member 10 which is reciprocally mounted in a substantially cylindrical casing 11 having diametrically disposed bosses 12—13 formed integral therewith proximate to the upper end thereof to threadedly receive handle members 14—15. The casing 11 has, in this instance, threadedly attached end caps 16—17 which close the interior bore or air cylinder 18 of the casing 11.

40 As shown, the casing 11 has an axially disposed tube 19 in threaded engagement with an axially threaded bore 20 provided in the lower end cap 16 to rigidly support the tube or sleeve 19 that serves as a guide for the central shaft or shank 10 which projects therethrough to provide a threaded extension 21 to which an anvil 22 is threadedly connected to serve as a weighted anvil for the shank or shaft 10.

45 The anvil 22 is sized to freely slide within an end bore 23 of a sleeve 24 that extends for the length of the casing cylinder 18 to present a peripheral stop or shoulder 25 proximate to the upper end of the casing cylinder 18. The peripheral stop or shoulder 25 provided in the sleeve 24 serves to

limit the descent of the weighted end member 22 of the shaft 10 and thus limit its reciprocal stroke between the peripheral sleeve shoulder 25 and interior end surface 26 of the casing end cap 17. It should be observed that the central guide tube or sleeve 19 terminates substantially in alignment with the peripheral sleeve shoulder 25 so that the weighted end member 22 will be free to reciprocate within the limits of the open end bore 23 of the sleeve 24.

It should be noted that bore 23 of the sleeve 24 communicates with a slightly smaller bore 27 that is sized to freely receive the upper section 28 of an impact hammer piston 29. The upper section 28 of the impact hammer piston 29 has an axial bore 30 therein that is sized to slide over the guide tube or sleeve 19 to impact against the anvil 22 of the shaft or shank 10 to effect hammer-like vibratory contact therewith so that repeated impacts will gradually move the central shank or shaft upwardly or toward the upper end casing cap 17. The hammer piston 29 has a somewhat larger lower section 31 which is complementary in size to the lower bore region 32 of the sleeve 24 so that the hammer piston 29 will be fully guided throughout its reciprocal stroke. The stroke of the hammer piston 29 is limited by an interior surface 33 provided on the lower end cap 16 which limits the descent of the hammer piston 29. The ascent of the hammer piston 29 is limited by the impact of its upper section 28 against the weighted anvil 22 of the central shank or shaft 10, and the latter, in turn, is limited by the end surface 26 provided on the upper end cap 17, thereby serving to impart driving impacts to the shaft 10 in a series of successive reciprocations that result in a vibratory driving action against the weighted anvil 22 to accomplish the intended pulling operation.

As shown, the hammer piston 29 has an enlarged bore 34 extending from its lower end to a position proximate to the upper section 28 thereof to provide an air space around the guide tube or sleeve 19. The air space 34 communicates with a plurality of radially disposed ports 35, in this instance four, that extend transversely through the hammer piston 29 to communicate with an annular space 36 defined by the somewhat enlarged sleeve bore 32 and an annular groove 37 that is provided in the circumference of the hammer piston 29 proximate to the upper solid section 28 thereof. The annular air space 36 communicates with a restricted circumferential air space 38 provided around the central region of the hammer piston 29 to communicate with an annular groove 39 provided in the hammer piston 29 between the lower solid section 31 thereof and its mid-section 40. Consequently, the circumferential air space 38 terminates in a peripheral shoulder defined by the annular groove 39 at its junction with the enlarged lower hammer section 31 against which the air pressure exerts a downward urge to displace the hammer 29 to its lowermost limit of movement against the end cap surface 33.

With the hammer piston 29 in its lowermost position, the interior sleeve bore 27 is free to exhaust the air through a plurality of radial ports 41, in this instance four, provided in the wall of the sleeve 24 to coincide with aligned ports 42 corresponding in size, number and position in the wall of the casing 11 to exhaust the air to the exterior atmosphere. Air under pressure from any suitable source, such as a receiver, is directly connected to an air compressor which supplies

air under pressure of from fifty to one hundred pounds per square inch to any length of rubber or other flexible hose that terminates in a nipple 43 that connects through a union 44 to an intake nipple 45 threadedly or otherwise attached to an intake orifice 46 comprising part of the handle hub or boss 13. The intake orifice 46 communicates with a valve seat 47 that has a ball check valve 48 co-operating therewith.

With this arrangement, the incoming air pressure normally seats the ball check valve 48 to close a port 49 that communicates with an intake passage 50. The intake passage 50 is disposed longitudinally through the handle hub 15 or boss 13. A threaded set screw 51 normally closes the intake passage 50, and such provides access thereto for cleaning or other purposes. A valve actuator rod 52 projects radially through the handle hub or boss 13 to extend into the port 49 that communicates with the valve seat 47 to actuate the ball check valve 48 responsive to the displacement of a hand lever 53 that is pivoted as at 54 to an ear 55 comprising a fillet between the handle hub 13 and the casing 11 (Figure 1).

As shown, the lever 53 is proximate to the handle 15 to enable the control thereof without the attendant removing his hand from the handle 15. Consequently, air can be admitted into the casing 11 to the intake passage 50 by merely depressing the lever 53 toward the handle 15. Air under pressure will occupy a circumferential chamber 56 which surrounds the sleeve 24 to enter interconnected air chambers 34-36-38 through a plurality of radial ports 57, in this instance four, provided in the sleeve 24 proximate to its central region. This will force the hammer piston 29 upwardly to its extreme uppermost position which is determined by its contact with the weighted end member 22, that, in turn, is limited by the upper end cap 17. In this extreme position, the air pressure in the chamber 34 and so much thereof as is beneath the piston or hammer 29 is exhausted through the ports 35-41-42. The air pressure in the chamber 56 is then exerted in the restricted circumferential chamber 38 that communicates with the annular hammer piston groove 39 to force the hammer piston 29 downwardly until it assumes its lowermost extreme position against the interior surface 33 of the lowermost end cap 16. This downward movement of the hammer piston 29 is followed by the shaft 10 with its weighted end member 22 that descends responsive to the urge of gravity, since the device is always used in a vertically erect position to pull sleeves or other articles upwardly. The hammer piston 29 is again ready for its upward movement under pressure for the reasons heretofore described, and this cycle of operations continues in a series of rapid reciprocations while the control lever 53 is depressed toward the handle 15. This results in vibratory impacts being imparted to the weighted end member 22 which transmits corresponding impacts to the shaft 10.

As shown, the shaft 10 terminates in a threaded end portion or shaft extension 59 that has a safety nut 60 threaded thereon in a position that will preclude contact with the lower end cap 16 while the device is in normal operation. Should it occur that the upper end cap 17 is broken or otherwise impaired so that the weighted end member 22 with its shaft 10 is not stopped by the end cap 17, the safety nut 60 will be in a position to contact the lower end cap 16 and

preclude injury to the operator whose body is disposed above the upper end cap 17. It will be observed, therefore, that the safety nut 60 serves merely to preclude the shaft 10 with its anvil 22 to be displaced upwardly through the casing 11. Should this occur, great injury could be caused to the attendant or operator who is holding the casing 11 through the medium of the handle members 14-15. The threaded shaft extension 59 is utilized to connect any suitable instrumentality thereto.

In the present embodiment, an interiorly threaded sleeve 61 is attached to the lower threaded end portion 59 of the shaft 10 to enable the attachment of any suitable pulling device thereto such as a sleeve puller engaging cap 62 that, in this instance, has stepped peripheral shoulder 63-64 intended to engage the lowermost edge 65 of a cylinder sleeve 66. The cylinder sleeve 66 is of the type that is pressed into the cylinder bore 67 of the crank case 68 of an internal combustion engine. It should be noted that the sleeve puller engaging cap 62 has tangentially flat parallel surfaces 69-70 (Figures 1 and 3) that permit it to be tilted for displacement downwardly through the interior of the sleeve 66 until the stepped shoulders 63-64 can engage the lower parallel sleeve edge 65 of the cylinder sleeve 66.

To this end, the puller engaging cap 62 is mounted on a threaded stud 70 having a retainer nut 71 thereon. The other end of the threaded stud 70 terminates in a circular swivel plate 72 (Figures 1 and 4) which cooperates with complementary furcations 73-74 formed integral with a stud 75. The stud 75 terminates in a threaded portion 76 which engages the other end of the correspondingly threaded sleeve 61 for attachment to the reciprocally mounted shaft 10. A bolt 77 extends through the furcations 73-74 and the circular swivel plates 72 of the lowermost stud 70 to pivotally connect the sleeve puller engaging cap 62 to the shaft 10. The successive vibratory impacts of the shaft 10 imparted by the hammer piston 29 will serve to pull the cylinder sleeve 66 from its cylinder bore 67 until the complete removal thereof is effected. As the sleeve 66 is successively pulled from its cylinder bore 67, the operator or attendant lifts the handles 14-15 in order that contact is maintained between the puller engaging cap 62 and the cylinder sleeve 66, although the operator does not have to exert any lifting force other than that which is necessary to maintain the puller engaging cap 62 in constant contact with the lower parallel edge 65 of the cylinder sleeve 66.

In the modified embodiment shown in Figure 2, the casing 11' is similar in construction and operation in all respects with the embodiment described supra. In this case, however, the central shaft 10' has a much longer threaded shaft extension 59' for adaptation to a different type of article engaging puller. In this instance, the shaft extension 59' carries a hub body 78 that has an axial threaded bore 79 that is complementary to the threaded shaft extension 59'. A plurality of bifurcated bracket members 80, in this instance three, radially extend from the hub body 78 to carry arcuate lever arms 81, as at 82, to the bifurcated brackets 80. The arcuate lever arms 81 terminate downwardly in inwardly directed hooks 83 that are intended to engage the peripheral edge portion 84 of a spur gear or other type of article 85 while the shaft extension 59' has its extremity 86 abutting against the part, such as

a shaft 87, on which the gear or other article 85 is press-fitted.

It should be noted that the extension extremity 86 momentarily holds the fixed part such as the shaft 87 relative to the movable part such as the gear 85 so that there is an initial impacting force that tends to loosen the movable part 85 from the fixed part 87. In situations where the part such as the shaft 87 is anchored against movement or is an element of a substantially weighted assembly, the central shaft extension 59' need not abut or be utilized to hold the part from which the article 85 is pulled from its fixed part 87 by the vibratory impacts that are effective in the manner described in connection with the removal of the cylinder sleeve 66 in the previous embodiments.

It is worthy of note that the tube or sleeve 19 not only serves as a guide for the shafts 10 or 10', but such also forms an air seal to the cylinder 11 or 11', respectively. Numerous and varied types of attachments can be utilized in conjunction with the extension shaft 59 or 59', depending upon the nature or shape of the article to be pulled therewith. That may be varied within a wide range, depending upon the commercial practices and the uses to which the device is put. It should be noted that in this modified embodiment, the manual valve actuator rod 52 instead of a lever 53 as illustrated and described in connection with the previous embodiment; however, this depends upon the choice of the manufacturer or user or the dictates of commercial practice.

It will be observed, therefore, that the arrangement of parts above described in conjunction with the illustrated embodiments effectively and readily pull various articles without any appreciable effort on the part of the operator and within minimum time requirements.

While I have illustrated and described a preferred embodiment of this invention, it must be understood that the invention is capable of considerable variations and modifications without departing from the spirit of the invention. I, therefore, do not wish to be limited to the precise details of construction set forth, but desire to avail myself of such variations and modifications as come within the scope of the appended claims.

I claim:

1. In a power pulling device or the like, the combination with a cylindrical shank for attachment of pulling members and the like, of an air cylinder surrounding a portion of said shank, an anvil in said air cylinder attached to said shank, a cylindrical sleeve axially disposed in said air cylinder for a portion of its length short of one end to allow for the displacement of said anvil between said sleeve and the end of said cylinder, said sleeve serving as a guide for said puller shank, a hammer piston within said cylinder and slidably enveloping said axial sleeve, and compressed air inlet and exhaust ports in said cylinder to intermittently displace said cylindrical shank by displacement of said hammer piston against said anvil for the purpose set forth.

2. In a power pulling device or the like, the combination with a cylindrical shank for attachment of pulling members and the like, of an air cylinder surrounding a portion of said shank, an anvil in said air cylinder attached to said shank, a cylindrical sleeve axially disposed in said air cylinder for a portion of its length short

of one end to allow for the displacement of said anvil between said sleeve and the end of said cylinder, said sleeve serving as a guide for said puller shank, a hammer piston within said cylinder and slidably enveloping said axial sleeve, compressed air inlet and exhaust ports in said cylinder to intermittently displace said cylindrical shank by displacement of said hammer piston against said anvil for the purpose set forth, and displacement limiting means on said shank in the path of said cylinder to serve as a safety expedient in conjunction with said impacting member.

3. In a power pulling device or the like, the combination with a cylindrical shank for attachment of pulling members and the like, of an air cylinder surrounding a portion of said shank, an anvil in said air cylinder attached to said shank, a cylindrical rigid sleeve axially disposed in said air cylinder for a portion of its length short of one end to allow for the displacement of said anvil between said sleeve and the end of said cylinder, said sleeve serving as a guide for said puller shank, a hammer piston within said cylinder and slidably enveloping said axial sleeve, there being radial ports in said hammer piston in communication with an annular channel thereon, and compressed air inlet and exhaust ports in said cylinder to intermittently displace said cylindrical shank by displacement of said hammer piston against said piston for the purpose set forth.

4. In a power pulling device or the like, the combination with a cylindrical shank for attachment of pulling members and the like, of an air cylinder surrounding a portion of said shank,

5
